UNITED STATES PATENT OFFICE.

WESLEY C. CRAWFORD, OF METAMORA, INDIANA.

LIFTING-JACK.

SPECIFICATION forming part of Letters Patent No. 555,802, dated March 3, 1896.

Application filed September 6, 1895. Serial No. 561,605. (No model.)

To all whom it may concern:

Be it known that I, WESLEY C. CRAWFORD, a citizen of the United States, residing at Metamora, in the county of Franklin and State 5 of Indiana, have invented certain new and useful Improvements in Lifting-Jacks; and I do declare the following to be a full, clear, and exact description of the invention, such as will enable others skilled in the art to which 10 it appertains to make and use the same, reference being had to the accompanying drawings, and to the letters of reference marked thereon, which form a part of this specification.

15 This invention, while relating to lifting-jacks generally, is especially directed to improvements in that class of jacks which are employed in connection with wagons and other vehicles.

20 The invention has for its object the production of a device of this character possessing advantages in point of simplicity and cheapness of construction and effectiveness in action, and added to these the device requires 25 but the minimum of power in its operation, is light of weight, and, having comparatively very few parts, is not liable to disorder.

The nature of my invention will become 30 clearly apparent from a reading of the following detailed description when taken in connection with the accompanying drawings, in which—

Figure 1 is a perspective view of my improved jack. Fig. 2 is an elevation of the 35 jack with the position it assumes before lifting in full lines and with the position it assumes after lifting in dotted lines. Fig. 3 is an elevation of the rear side of the jack, a portion being cut away to show the preferred means 40 for vertical adjustment.

Referring to the said drawings by letter, A denotes the standard which supports the working parts and receives the weight of the wagon or other body. Said standard is preferably of rectangular form, and is provided 45 with any suitable means for vertical adjustment, the preferred means being to form the standard in two parts, the upper one of which, a, has a tongue a' slidably arranged in a recess a² in the lower part, a³. The lower part 50 and the tongue a' are provided with transverse holes a⁴ a⁴ through which is passed a

latch pin or pins b, the latter thereby supporting the upper part at any desired height. On the outer sides of the lower part are plates 55 c c which form walls for the recess a². Near the top of the upper part, a, is a pin d which projects beyond each side of said part and forms a journal for a loosely-mounted wheel e and a pivot for the operating-lever f. For 60 convenience in construction the pin is in the form of a headed bolt, the end of which is threaded and has a nut d'. That corner of the standard adjacent to the wheel and the pivotal point of the lever is rounded off concentrically with the periphery of the wheel, but the radius of said rounded portion is less 65 than that of the wheel, in order that said wheel may project slightly beyond the standard, for a purpose presently to be explained.

70 The operating-lever is pivotally arranged on the side of the standard opposite to the wheel, and the inner end f' of said lever is of sufficient length to project beyond the standard and the periphery of the wheel. Said end, 75 however, may be shortened at will as I form in the lever a longitudinal slot f² which receives the pivot-pin d.

As before stated, the standard is generally 80 rectangular in shape and is of sufficient width to provide a broad foot or base, in order that the device when vertically placed may so remain.

In the operation of lifting—such, for instance, as a wagon body—the device is placed 85 in the inclined position shown in full lines in Fig. 2, with the lower corner x on the ground or floor, directly beneath the axle, and the lifting end f' of the lever and the periphery of the wheel engaging the axle. With the 90 parts in this position the handle end of the lever is depressed and the lifting end is consequently elevated and raises the axle and body until the weight of the latter is shifted from the lever to the wheel, which revolves 95 under the movement of the body by its contact with the axle. As soon as the wheel receives the weight of the body its further revolution causes the standard to automatically right or assume a vertical position, and finally 100 the axle, leaving the wheel, finds support on the top of the standard beyond the wheel, as clearly shown in dotted lines in Fig. 2, and the operation is completed. The employ-

ment of the slot in the lever insures the proper operation of the device at all times, inasmuch as the axle or other weight to be raised may be always brought into contact with the wheel 5 by shortening the lifting end of the lever.

From the foregoing it will be evident that manual power is necessary only to start the device, or, in other words, the lever is out of operation as soon as the axle which is in engagement with the wheel shall have passed 10 the dead-center, so to speak, after which the automatic restoration of the vertical position of the standard completes the elevation of the wagon-body.

15 I claim as my invention—

1. A lifting-jack comprising a standard, a wheel mounted at one side of the upper end thereof and projecting beyond said end, and a lever the lifting end of which projects beyond 20 the periphery of the wheel.

2. A lifting-jack comprising a standard ver-

tically adjustable and having a rounded upper corner, a wheel mounted on the standard and projecting beyond said corner, and a lever pivoted on the opposite side and having 25 its lifting end projecting beyond the periphery of the wheel.

3. A lifting-jack comprising a vertically-adjustable standard having a broad base and a curved upper corner, a wheel mounted on a pin 30 and projecting beyond said curved corner, and an operating-lever having a slot through which said pin passes, the lifting end of the lever projecting beyond the periphery of the wheel. 35

In testimony whereof I affix my signature in presence of two witnesses.

WESLEY C. CRAWFORD.
